William H. Odlum, Wilmette, and Karl A. Paine, Jr., Park Ridge, Ill., assignors to Duro Metal Products Company, Chicago, Ill., a corporation of Illinois

Application July 11, 1952, Serial No. 20,560

Term of patent 14 years

(Cl. D54—2)

To all whom it may concern:

Be it known that we, William H. Odlum and Karl A. Paine, Jr., both citizens of the United States and residents, respectively, of Wilmette and Park Ridge, in the county of Cook and State of Illinois, have invented a new, original, and ornamental Design for a Tool Support, of which the following is a specification, reference being had to the accompanying drawing, forming part thereof.

Fig. 1 is a perspective view of a tool support showing our new design;

Fig. 2 is a front elevational view thereof;

Fig. 3 is a rear elevational view;

Fig. 4 is a top plan view;

Fig. 5 is an end elevational view; and

Fig. 6 is a bottom view thereof.

We claim:

The ornamental design for a tool support, substantially as shown.

WILLIAM H. ODLUM.
KARL A. PAINE, JR.
